(57) **CLAIM**

The ornamental design for a tandem fish hook, as shown and described.

DESCRIPTION

FIG. 1 is a perspective view of a first embodiment of the tandem fish hook;

FIG. 2 is a front view of FIG. 1, with the rear view being identical;

FIG. 3 is a left side view thereof;

FIG. 4 is a right side view thereof;

FIG. 5 is a top view thereof;

FIG. 6 is a bottom view thereof;

FIG. 7 is a perspective view of a second embodiment of the tandem fish hook;

FIG. 8 is a front view of FIG. 7, with the rear view being identical;

FIG. 9 is a left side view thereof;

FIG. 10 is a right side view thereof;

FIG. 11 is a top view thereof;

FIG. 12 is a bottom view thereof;

FIG. 13 is a perspective view of a third embodiment of the tandem fish hook;

FIG. 14 is a front view of FIG. 13, with the rear view being identical;

FIG. 15 is left side view thereof;

FIG. 16 is a right side view thereof;

FIG. 17 is a top view thereof; and,

FIG. 18 is a bottom view thereof.

Features shown in dashed lines in FIGS. 7-12 are for illustrative purposes only and form no part of the claimed design.

1 Claim, 3 Drawing Sheets
